UNITED STATES PATENT OFFICE.

HENRY RABINOWITZ, OF BROOKLYN, NEW YORK.

WINDOW.

1,278,210.

Specification of Letters Patent. Patented Sept. 10, 1918.

Application filed June 19, 1916. Serial No. 104,556.

To all whom it may concern:

Be it known that I, HENRY RABINOWITZ, a citizen of the United States, residing at 705 Georgia Ave., Brooklyn, in the county 5 of Kings and State of New York, have invented a new and useful Window, of which the following is a specification.

My invention consists in the novel features hereinafter more fully described.

10 The objects of my improvement are:

First: To produce a window, which can be cleaned from the inside, without any danger of falling out.

Second: To have said window weather- 15 proof.

Third: To have said window simple, durable and inexpensive.

Fourth: To allow an air space in the middle of the window.

20 I attain these objects by the window, one form of which is illustrated in the accompanying drawings or by any mechanical equivalent or obvious modification of the same within the scope of my invention.

25 Figure 1 is a vertical section on the line A—B of Fig. 2 except that the detail 19 is shown as a vertical section through C—D of Fig. 2.

Fig. 2 is a horizontal section through 30 E—F of Fig. 1.

Fig. 3 is a vertical section on the line I—J of Fig. 1; it is shown as broken in two places.

35 Fig. 4 is a vertical section on the continuation of the line A—B of Fig. 2 through the other side of the window casing, showing the jamb 16 displaced.

Fig. 5 is an elevation of one of the toggle joints shown in Figs. 1 and 4.

40 Figs. 6 and 7 are vertical sections through the line K—L of Fig. 10, but showing one of the jambs 16 displaced.

Fig. 8 is an elevation of the toggle joint 30^a shown in Figs. 6 and 7.

45 Fig. 9 is a vertical section through the line M—N of Fig. 10.

Fig. 10 is a horizontal section through O—P of Figs. 6, 7 and 9.

Fig. 11 is a side elevation of the key 60.

Fig. 12 is a front view of the key-plate 58. 50

Similar numerals and letters refer to similar parts through the several views, as follows:

11 and 12 are the outer walls of the window casing. 55

13 is the stationary jamb shown at the left in Fig. 1.

14 is a detachable plate, covering an opening in the lower part of said jamb 13; this opening is provided for allowing the sash 60 weights 27 and 27^a to be inserted into and removed from the chamber inclosed by the wall 11, jamb 13 and the vertical covers 34 and 35 shown in Fig. 2.

15 is the upper part of the jamb shown 65 to the right of the window in Fig. 1, which part 15 is also shown as stationary.

16 is the lower part of the jamb shown to the right of the window in Fig. 1, which part 16 is shown in Fig. 5 as being movable; 70 the lower end or bottom of said movable jamb 16 is adapted to slide in the cut out 17^a of the sill 17; the upper end of said jamb 16 has a sliding strip 32 connected thereto; both the jamb 16 and the sliding strip 32 75 are adapted to slide on the underside of the guide board 31, shown in Figs. 1, 4, 6 and 7.

18 is a horizontal weather strip shown in Figs. 4, 6 and 7.

19, 19^a 19^b, 20, 20^a, 20^d and 20^b are vertical 80 weather strips; 19, 19^a, 19^b and 20^a also 20^b are stationary; 20 and 20^d are movable together with said jamb 16, to which they are attached.

21 is the upper top of the inner part of the 85 window casing; 22 is the lower top; the former limits the upward motion of the inner window sash 24; the latter limits the upward motion of the outer window sash 23.

The relative positions of the tops 21 and 90 22 are most clearly shown in Fig. 3; they are shown as placed at different elevations for two reasons: first, to allow an air space in the middle part of the window when the inner sash 24 is moved upward and the outer 95 sash 23 downward; second, to allow the outer sash 23 when in the lower position to be revolved on a vertical axis, as hereinafter

described, and to clear the weather strip 18 below it and the bottom of the sash 24 above it.

25 are handles on said sashes 23 and 24 for revolving the same on a vertical axis into a position convenient for cleaning the panes 47 from the inside.

26 is the cord attached at one end thereof to the sliding member 40, hereinafter described, and at the other end to the sash weight 27.

26^a is the cord attached at one end thereof to the sliding member 41, hereinafter described, and at the other end to the sash weight 27^a.

28 and 28^a are the pulleys for said cords 26 and 26^a respectively.

29 are bearing plates shown in Figs. 1 and 4 as secured to the inner sides of said movable jamb 16 and said casing 12, opposite each other.

30, 30 are toggle links shown in Fig. 5 as pivotally connected to each other by means of the spindles 30^a and to said plates 29 by 25 means of the spindles 29^a and 29^b.

The spindle 29^b is shown in Fig. 5 as having a square end, which is adapted to fit a suitable key.

It is evident that when the pin 29^b is 30 turned in a certain direction, the toggle joint 30 will change its position from that shown in Fig. 1 to that shown in Fig. 4, thereby causing the movable jamb 16 with the weather strip 20 to slide away from the sashes 23 and 24 toward the casing 12; the sashes 23 and 24 are in this way made to clear the weather strip 20. Instead of moving the full width of the jamb 16, shown in Figs. 1 and 4, which jamb is similar to that 40 shown in Fig. 10, any convenient part of it, with the weather strip 20 attached to it, may be moved.

33 is a connecting rod, shown in Figs. 1, 4, 6 and 7 as connecting the upper and lower 45 toggle joints, so that, by operating one of these toggle joints by means of a suitable key acting on the spindle 29^b above described, the other toggle joint will move likewise, thereby moving the plates 29 secured 50 to the jamb 16 in a parallel direction.

36 designates the bearing plate for supporting the pulley 28^a.

37, 38 and 39 are vertical guides for the sliding members 40 and 41, shown in Fig. 52; and located at the outer side of the hinge boxes 42, which are shown in Figs. 1 and 2 as inserted into the frame of each of the sashes 23 and 24 at one side thereof.

43, 43 are the front and rear covers of 60 said hinge boxes 42; they are shown in Fig. 2.

When the jamb 16 with the weather strip 20 is made to clear the window sashes 23

and 24 a requisite distance, as shown in Figs. 4, 6 and 7, the sashes or either of them, are 65 pulled away from the jamb 13, shown in Fig. 1, thereby pulling the hinge boxes 42 and causing the hinges to open up, when the sash 23 or 24 is revolved into any convenient position for cleaning the pane 47. 70

In the construction of my window, as shown in the drawings, only one sash at a time may be made to clear the weather strips 19 and 20 and then revolved, as above described.

To bring the other sash into a similar position, the first sash is pushed upward, thereby causing the corresponding sliding member 40 or 41 to slide upward until said first sash clears the upper end of the movable jamb 16; the other sash is then brought down opposite to said movable jamb 16, and the operation above described is repeated.

The cords 26 and 26^a above described are fastened each at one end thereof to the corresponding sliding members 40 and 41, which are connected to the corresponding sashes 23 and 24 by means of extensible hinges and hinge boxes 42 above described.

The sashes 23 and 24 are provided at their 90 upper sides with openings 24^b and 24^a respectively, shown in Fig. 2, and extending some distance downwardly, to make room for the ends of said cords 26 and 26^a and to pass the portions of the pulleys 28 and 95 28^a, which project beyond the face of the jamb 13.

47 are the window panes, shown in cross-section in Figs. 2 and 3.

48 is a horizontal weather strip shown in 100 Fig. 3 as connected to the underside of the lower top 22.

49 is a horizontal groove, shown in Fig. 3 as located in the upper side of the sash 23 and adapted to fit said weather strip 48. 105

50 is the vertical cover in the rear of the upper end of the space, in which the sash 24 may be moved.

Where two windows are situated close together with a narrow space between them I 110 provide the arrangement shown in Figs. 6 and 7, whereby the same set of toggle joints is made to operate alternately both jambs 16 and weather strips 20 and 20^d thereby clearing the sashes of both windows, and thereby saving the space, which would otherwise be necessary, if the arrangement shown in Fig. 1 were used for each of the two windows.

51 is a strip shown in Figs. 6 and 7 as secured to the sill 17 to limit the motion of either of the movable jambs 16. 120

52 is a sliding strip shown in Figs. 6 and 7 as secured to the upper end of each of the movable jambs 16 and sliding on the underside of the guideboard 31; the strips 52 of 125

Figs. 6 and 7 are similar to the strip 32 of Fig. 1.

Figs. 6 and 7 show the alternate positions of each of the opposite jambs 16, which are 5 operated by means of the key 60, shown in Fig. 11, engaging the square end of each of the spindles 29^b, above described.

To prevent any lateral and twisting strains on said movable jambs 16 from being produced by the action of said key 60 on 10 said spindles 29^b, I provide the forks 53, which are shown in Figs. 6, 7 and 9, and the openings 53^c in the rear wall 54 of the toggle chamber, as shown in Fig. 9.

15 53^a is a horizontal bar connected at one end thereof to said fork 53 and terminating at the other end in a short column 53^b under said spindle 29^b, as shown in Fig. 9.

The bar 53^a is shown in Fig. 9 as sliding 20 in a guide 64 and is encompassed by a spring 63, which is shown as abutting at one end thereof against said column 53^b and at the other end against said guide 64, which is secured to the jamb 16.

25 The spring 63 tends to keep the prongs of the fork 53 normally out of the openings 53^c; but, when the key 60 is applied to the spindle 29^a, it first pushes said column 53^b inwardly against the pressure of said spring 63, thereby causing the prongs of the fork 53 to enter said openings 53^c, and thereby securing one of the jambs 16, which is to be kept stationary for the while, against any strains and motion.

30 35 The same operation is performed alternately on the fork slidably connected to the other jamb 16 by means of the guides 29^c when the latter is to be kept stationary.

56 are a pair of vertical weather strips 40 shown in Figs. 9 and 10 as secured each to one of the movable jambs 16.

57 are a pair of vertical weather strips shown in Fig. 10 as secured to the edges of the front cover 55.

45 61 is a tooth on said key 60, shown in Fig. 11; it serves to prevent the key 60 from being disengaged from the square end of said spindle 29^b by the pressure of the spring 63 against said column 53^b, shown in Fig. 9.

50 It is evident that where both jambs 16 are movable as in Figs. 6, 7 and 10, two spindles 29^b are provided with square ends as shown in Fig. 8 in elevation; but where one jamb only is movable, as in Figs. 1 and 55 4, only one spindle 29^b is provided with a square end as shown in Fig. 5.

58 is a suitable key plate shown in Figs. 9 and 12; it has an opening 59 for said key 60 and a notch 59^a for the tooth 61 of the 60 key 60 to pass through.

60^b is an opening in said key 60, which opening fits the square end of said spindles 29^b.

62 is a handle for turning said key 60.

65 is a trolley on the upper edge of each 65 of the sashes 23 and 24 to reduce friction in sliding the same.

I do not therefore restrict myself to the design of the details as shown in the drawings; but I intend to include also all mechanical equivalents and obvious modifications of the same.

What I claim as my invention and desire to secure by Letters Patent, is:—

1. A window frame having a horizontally 75 movable section, a toggle joint, adapted to move said section horizontally without lifting the same, and means co-operating with said toggle joint to prevent the lifting of said section.

2. A window frame having two sash openings and an intermediate chamber, having 80 movable side walls forming a portion of the jambs and carrying a portion of the weatherstrips, combined with a means 85 whereby said jamb sections may be moved alternately into and out of operative positions.

3. A window frame having a horizontally 90 movable section, a toggle joint adapted to move said section horizontally and a key for operating said toggle joint, said toggle joint normally having its two links in a straight line, thereby preventing the moving 95 of said section without applying said key to said toggle joint.

4. A window frame having a horizontally 100 movable section, a toggle joint adapted to move said section horizontally without lifting the same, a key for operating said toggle joint, said toggle joint normally having its two links in a straight line, thereby preventing the moving of said section without applying said key to said toggle joint, and a horizontal guide board at the upper end 105 of said section, said guide-board being adapted to co-operate with said toggle joint to prevent the lifting of said section while moving the same.

5. The combination of a window frame 110 having a horizontally movable section, a pair of toggle joints adapted to move said section horizontally without lifting the same, a key adapted to be applied to one of the lateral pivots of one of said toggle joints, thereby simultaneously actuating both toggle joints, each of said toggle joints 115 normally having its two links in a straight line, thereby preventing the moving of said section without applying said key to said toggle joint, and a rod connecting the central pivots of each of said toggle joints, said rod being adapted to facilitate the starting 120 of the motion of said toggle joints when said key is applied.

6. A window frame having two sash open-

ings and an intermediate chamber having movable side walls forming a portion of the jambs and carrying a portion of the weatherstrips, a means, whereby said jamb sections may be moved alternately into and out of operative positions, and a means for automatically locking each of the movable sections to the frame while moving the other section.

10 7. A window frame having two sash openings and an intermediate chamber, having movable side walls, forming a portion of the jambs, and carrying a portion of the

weather strips, a means whereby said jamb sections may be moved alternately into and out of operative positions, and a means for locking each of the movable sections to the frame while moving the other section, said locking means comprising a suitable fork carried by each of said jamb sections, said fork being adapted to be projected into corresponding openings in said frame, thereby locking said jamb to said frame, and a means for keeping said fork normally out of said openings.

HENRY RABINOWITZ.

Copies of this patent may be obtained for five cents each, by addressing the "Commissioner of Patents, Washington, D. C."
